SAMUEL G. PAYNE, OF HOWARD, RHODE ISLAND

COLLAR AND THE LIKE

Application filed November 12, 1926. Serial No. 148,053. Renewed January 10, 1930.

In classifying my present invention as related to the so-called soft collar art, it is only necessary to state that it has to do with the much considered feature of foldability in such collars, and as this subject has been so much considered in prior patents and adjudications thereof, no general statements of the problems are required as a preface to my present discussion.

In my present invention I have departed from the general previous conception of establishing a definite line of fold in a collar. The difficulty with such a conception lies in the varied contour of the neck of the wearer which so varies the set of any commercially made collar that any predetermined definite line can have no more than an average of approximate fit. My present invention may, therefore, be said to contemplate a collar capable of fold in a predetermined area with such variance as will provide accommodation for the individual contour of the neck of each wearer.

To this end my invention contemplates a development in the field of the stretch in fabrics. The factor of shrinkage has been considered but for commercial purposes the results have been so widely variant that commercial success has not been possible. In my present invention I deal with stretchability as distinguished from shrinkage. For the purposes of my present disclosure I have provided drawings somewhat diagrammatic in character as illustrative of simple forms of my invention and to these drawings I make reference by usual characters similarly applied throughout. In the drawings:

Fig. 1 is a plan view of a collar of the type specified.

Fig. 2 a view of such a collar folded and bent.

Fig. 3 a fragment showing one form of stretch retardation.

Fig. 4 a similar view showing another modification, and

Fig. 5 a further modification.

In such a collar as is indicated in Fig. 1 I have indicated it as comprising a neck band portion 1 and an overfold portion 2. I have also indicated the rear collar buttonhole at 3

and the front collar buttonholes at 4. I have also indicated in Fig. 1 by a broken line A—A, what might be considered as the limit of line of fold in one direction. The dotted and dash line B—B may be considered as the extreme 55 line of fold in the other direction. These lines are merely illustrative and intended to convey the idea that for different necks the fold may shift considerably. Such folds are usually governed as at X—X by suitable form 60 or construction at the ends of the collar and for that reason the lines are shown as meeting or approximately meeting at that point.

I have indicated by the lines T threads which extend generally at an angle to the 65 lines A—A and B—B, so that they are oblique or diagonal of the collar. No effort is made to show exact fabric as special weaves are not necessary in my collar. In fact, while the collars may be woven in narrow fabrics 70 with a diagonal weave, they may be given the required curvature and configuration in accordance with the practice in such collar weavings. It will be understood that these collars can be made by simply cutting them 75 from broad fabric so that the weave is biased.

The point, therefore, is that whatever the method of making the fabric, whether woven or otherwise, the trend or direction of the thread should be in the collar at an angle to 80 the region of the fold. When so considered it will be seen that the threads T as in Fig. 1 cross each other so that considered from the line of fold they might be regarded as practically pivoted members. This gives to the 85 fabric a considerable degree of longitudinal stretchability which is principally effective at the edges of the collar as distinguished from what is generally termed as the line of fold.

In accordance with my invention I prefer to provide a retardant for this longitudinal stretchability in the region of the collar band 1.

In the case of simple collar structures, as where the collar is formed from a single fabric, this may be accomplished by a line of stitches S as appears in Fig. 3. The same general effect may be accomplished by applying any sort of a band or binding as S¹ shown in Fig. 4. Such a retardant in the collar 100

band provides a sufficient differential in the longitudinal stretch of the collar so that when the collar is folded, as in Fig. 2, the outside portion or overfold 2 can stretch sufficiently to conform to the band portion 1 whatever the line of the fold may be as it develops on the neck of the individual wearer.

In the modification shown in Fig. 3 the line of stitching S may be of simple stitch or of any more elaborate form as may be desired. Even a simple line of stitching will retard the stretch in that portion of the collar so as to accentuate the relative freedom of the overfold portion 2. In Fig. 4, the stretch retardant is a band which may be of cross woven fabric or fabric of any other type. Such fabrics should not of course be a longitudinally stretchable fabric, although any fabric when stretched to such a collar will act as a retardant.

From the above it will be seen that such collars when put on for wear simply find their own fold, the rest of the collar and particularly the overfold portion 2 conforming so as to lie smooth and fit tightly. Such collars will be found to fold naturally and freely and yet so definitely that the line of fold will be positive. I have not attempted in the drawings to show the relative displacements of the threads due to stretch. This is impracticable as the adjustment is rather slight in the fine threads but with the above explanation it will be understood by those skilled in the art and although the results may be unexpected they can be so readily tested that attempts at verbal demonstration is unnecessary.

In Fig. 5 I have shown a form of stitching which presents certain combined factors in that it is both a stretch retardant and a finishing stitch. Its particular importance is in connection with low priced collars as it is a satisfactory substitute for the overcasting of the raw edge as the usual practice before turning and stitching down. As shown, the stitch is laid by a so-called fagoting machine which produces on the turned edge of the collar a fagoting effect as indicated at S² while on the opposite face of the collar it produces a parallel row of stitches as s². The stitch S² is laid over a tape or cord C which prevents the stretch in the band portion of the collar. In such other portions as may be so stitched where stretch is desired the cord C is omitted. In this way the stitching down of the turn of the collar edge is effected while at the same time producing a longitudinal retardant for the stretch. This modification illustrates a group of possible variants which will be readily understood.

The modifications suggested are obviously merely a few of many variants that could be shown. The multiplication of such is omitted in the interest of simplicity. All such, however, are to be understood as within

the purview of my invention and to be within its scope as I intend to claim it.

What I therefore claim and desire to secure by Letters Patent is:

1. A one-piece collar presenting when overfolded upon itself, a neck band portion and an overfold portion, said neck band portion being provided with stretch retarding means for preventing stretching and permissive of longitudinal stretch in its areas above said retarding means, thereby causing the collar when stretched to assume a fan-like form, the fabric from which said collar is formed being cut on the bias continuously across the full width of the combined band portion and overfold portion to produce an increasing longitudinal stretchability in a direction from the retarding means on the band towards the outside of the overfold portion.

2. A one-piece collar presenting when overfolded upon itself a neck band portion and an overfold portion, said neck band portion having along its bottom edge only means for positively retarding longitudinal stretch thereof in said edge area only and permissive of longitudinal arcuate stretch in its areas above said retarding means, thereby causing the collar when stretched to assume a fan-like form, the fabric from which said collar is formed being cut on the bias continuously across the full width of the combined band portion and overfold portion to produce an increasing longitudinal stretchability in a direction from the bottom edge of the band portion towards the outside of the overfold portion resulting in a collar adapted to snugly fit the neck band of the shirt and to freely conform to the neck above the neck band of the shirt and to fold smoothly and uniformly and without wrinkles when worn.

In testimony whereof I affix my signature.

SAMUEL G. PAYNE.
